[57] CLAIM

The ornamental design for a hyperbaric therapy unit, as shown.

DESCRIPTION

FIG. 1 is an end view of a hyperbaric therapy unit embodying the new design;

FIG. 2 is an end view of the hyperbaric therapy unit shown in FIG. 1 in an alternative condition;

FIG. 3 is a side view of the hyperbaric therapy unit shown in FIG. 1;

FIG. 4 is a side view of the hyperbaric therapy unit shown in FIG. 1 in an alternative condition;

FIG. 5 is a plan view of the hyperbaric therapy unit shown in FIG. 1;

FIG. 6 is a plan view of the hyperbaric therapy unit shown in FIG. 1 in an alternative condition;

FIG. 7 is an isometric view of the hyperbaric therapy unit shown in FIG. 1; and

FIG. 8 is an isometric view of the hyperbaric therapy unit shown in FIG. 1 in an alternative condition.

FIG. 9 is an end view of the hyperbaric therapy unit embodying the new design from the opposite end of FIG. 1; and,

FIG. 10 is a side view of the hyperbaric therapy unit embodying the new design shown from the opposite side of FIG. 3.
